UNITED STATES PATENT OFFICE.

EDWARD J. BOWLES, ELMER METZ, AND HERMAN METZ, OF CLINTON, ILLINOIS.

BEADER AND GUTTER-FORMER.

1,267,368.

Specification of Letters Patent.

Patented May 28, 1918.

Application filed July 30, 1915. Serial No. 42,683.

To all whom it may concern:

Be it known that we, EDWARD J. BOWLES, ELMER METZ, and HERMAN METZ, citizens of the United States, residents of Clinton, in 5 the county of DeWitt and State of Illinois, have invented new and useful Improvements in Beaders and Gutter-Formers, of which the following is a specification.

Our invention relates to improvements in 10 beaders and gutter formers and the principal object of our invention is the provision of a simple and efficient mechanism of that type which will bead and form gutters or troughs with facility.

15 A further object is the provision of a device of this character in which a sheet of metal may be placed and beaded and then formed into a suitable gutter or trough, provision being made for suitable adjustments,

20 whereby troughs and gutters of different sizes may be made in one and the same machine.

A further object is the provision of a device of this character which includes a forming trough, a tubular form mounted and adapted to be pressed into said trough, a beading rod mounted on one side of said trough and an additional form on the other side of said trough, adapted to complete the 30 forming of the gutter.

A further object of our invention is the provision of a trough having means for varying its size and having a beading rod mounted adjacent one side thereof, a 35 forming cylinder pivotally and removably mounted on the same side of said trough and adapted to be forced into said trough to shape a sheet of metal, and an additional form on the other side of said trough adapted to be moved over said forming cylinder to complete the shaping of the gutter or trough section.

To the accomplishment of the foregoing and such other objects as may hereinafter 45 appear, our invention consists in the combination, construction and arrangements of parts hereinafter described, and then sought to be defined in the appended claims, reference being had to the accompanying drawings forming a part hereof, and which show merely for the purpose of illustrative disclosure, a preferred embodiment of our invention, it being understood that various changes may be made in practice within the

scope of the claims, without digressing from 55 our inventive idea.

In the drawings—

Figure 1 represents a perspective view of a machine constructed according to our invention, the forming roll being in forming 60 position;

Fig. 2 is a transverse vertical section of Fig. 1; the parts being shown in position before the blank is placed therein, in full lines, the dotted line position representing the 65 forming position of the parts;

Fig. 3 is a detail view of the means for operating and locking the beading rod.

Referring now to the drawings, the numeral 1 designates the legs or supports, on 70 which is mounted the base member 2 which is shown in the form of a channel and has the trough 3 mounted thereon. This trough is formed of two angle members 4 and 4', one of said angle members having the bolts 5 75 which pass through slots 6 in the channel member 2 having the securing nuts 7 and operating handles 8, whereby lateral adjustment is provided for varying the size of the trough, for a purpose which will hereinafter 80 appear.

The upper and outer edge of the vertical flange of angle member 4' is rounded as at 9 and merges into a housing 10 for the beading rod 11, this beading rod being provided 85 with the slot 12 to receive the edge of the sheet metal blank. This housing 10 is provided by means of an angle member 13 secured to the vertical flange of the angle member 4' of the trough by means of the 90 wing nuts and bolts 14, which permit the ready removal of the member 13 in case of accident.

Secured to the channel member 2 and the angle member 4' are the bracket members 15 95 which extend upwardly and pivotally support the elongated operating levers 16. These operating levers 16 are pivotally connected as at 17 to the member 18 between the pairs of spaced lugs 19, this member 18 being 100 secured to the forming roll 20, which is in the form of an elongated tube. This forming roll is adapted to be moved to and from the position shown in Fig. 2 of the drawing, by means of the operating levers 16, so as to 105 operate on a sheet metal blank and press the same into curved form within the sides of the trough.

Secured to the other side of the channel member 2 are the extended arms or bracket members 21 which support the guiding means 22. This guiding means is provided with 5 the bifurcated portion 23 to receive the roller 24 having the depending stud 25 passing through a slot 26 in bracket 21 and provided with the head 27. This guiding member also has the depending lug or projection 28 10 adapted to bear against the stop member 29 which may be placed at different positions on said arm or bracket member so as to adjust the position of the guide members, and limit their movement inwardly. The stop 15 members 29 comprise merely a rod, shaft or pin positioned in one of a number of apertures or holes in said bracket members.

Secured to the lug or projection 28 is the spring 30 which is also secured to a lower 20 portion of the arm or bracket 21, whereby the guide member is normally held toward the trough. The handle 31 is provided thereon so that it may be manually withdrawn. The arm or bracket member 21 is 25 provided with the inclined and extended portion 21' on which the guiding member is mounted, the inclination being at a suitable angle to give the best results.

We mount on the same side of the trough 30 as the guide members, the additional forming element 32, which is in the form of the angle member 33 having the operating arms or levers 34 secured thereto. This additional forming element is hinged to the angle member 4 of the trough by means of a plurality 35 of hinges 35 and has secured thereto, the plurality of curved lugs or wings 36, which pass through suitable slots in the angle member 4 of the trough to a position within the 40 trough to be engaged by the sheet metal blank when pressed downwardly by the forming roll 20. This will throw the operating levers 34 out to a position for convenient manipulation.

The beading rod is loosely mounted in the housing 10 and has the cranks 37 for operation. One of the cranks is provided with the flange 38 which is adapted to be engaged by the hooked lug 39 which is pivoted at 50 40 to the side of the trough and normally held in locked position as indicated in Fig. 3. This prevents the displacing of the beading rod when inserting the sheet metal blank.

The operation of forming and beading a 55 gutter section will now be explained. Assuming that the parts are in the position shown in full lines in Fig. 2, a sheet metal blank of suitable width is inserted with one edge in the groove 12 in the beading rod, the 60 guide members having been withdrawn manually so that the other edge engages in the rollers 24. The cranks 37 are then manipulated to form the bead on one edge of the sheet metal blank, and the operating levers 65 16 are then moved to the dotted line position

of Fig. 2 and full line position in Fig. 1, which forces the sheet metal blank into the trough, causing it to conform to the cross sectional shape of the roll 20. During this operation, the curved lugs or wings 36 are 75 engaged by the sheet metal blank and cause the additional forming element and its operating levers 34 to move outwardly and upwardly so that they may be readily grasped by the operators, who then lift the levers 34, 75 moving the parts to the dotted line position of Fig. 2, thereby forcing the free edge of the sheet metal blank around the roll 20. The parts are then returned to their full line position in Fig. 2 and the completed gutter 80 section withdrawn, completely beaded and formed.

As has been stated hereinbefore, the machine is adapted for the formation of various sizes of gutter sections and for that 85 purpose, the width of the trough may be varied, by means of the connection described for adjusting the position of the angle member 4. Spacing blocks 41 are inserted where necessary, and a roll 20 of the proper size is 90 attached to the lever 16, it being understood that the pivotal connection 17 is readily detachable. The guide members 22 are adjusted on the inclined portion 21' of the arm or bracket members 21, so as to accommodate the variation in width of the sheet metal 95 blank.

It is therefore seen that we have provided a mechanism which is simple in structure and operation, capable of various adjustments to form and bead different sizes of gutter sections. In case the blank buckles about the beading rod, the housing 10 may be readily removed.

What we claim is:—

1. A mechanism of the character described, including in combination, a trough, a beading rod mounted on one side thereof, a forming roll pivotally mounted on the same side thereof, means for forcing said forming roll into said trough, an additional forming element pivoted to the other side of said trough to form the other side of the blank, operating levers for said additional forming element, and means connected to 110 said additional forming element and extended into said trough and adapted to be engaged by the blank when the forming roller is in its lowermost position, so as to move said operating levers to a convenient 115 position for operation.

2. A mechanism of the character described, including in combination a trough into which a sheet metal blank is adapted to be forced, a beading rod mounted on one 125 side of said trough and adapted to form a bead in one edge of said blank, a forming roll pivotally mounted on said trough and means for forcing the said roll into said trough for forming said blank into a gutter 130

- section, conforming in cross-section to said forming roll, and an additional forming element on said trough and means for operating the same to force the unbeaded edge of 5 said blank about said forming roll, and lugs connected to said additional forming element and extended within said trough in position to be engaged by said blank when the forming roll approaches its lowermost 10 position, whereby the operating means for said additional forming element are moved to a position convenient for manipulation.
3. A mechanism of the character described, including in combination a trough 15 into which a sheet metal blank is adapted to be forced, a beading rod mounted on one side of said trough and adapted to form a bead in one edge of said blank, a forming roll pivotally mounted on said trough and means 20 for forcing the said roll into said trough for forming said blank into a gutter section conforming in cross section to said forming roll, and guides for holding the blank in proper position.
- 25 4. A mechanism of the character described, including in combination a trough into which a sheet metal blank is adapted to be forced, a beading rod mounted on one side of said trough and adapted to form a 30 bead in one edge of said blank, a forming roll pivotally mounted on said trough and means for forcing the said roll into said trough for forming said blank into a gutter section conforming in cross section to said 35 forming roll, and guides for holding the blank in proper position, said guides being resiliently and adjustably held.
5. A mechanism of the character described including in combination, a channel 40 base member, a plurality of supports therefor, a trough supported on said channel member, a beading rod mounted on one edge of said trough and adapted to form a bead on one edge of a sheet metal blank, a forming 45 roll pivotally mounted, means for forcing said forming roll into said trough to form the blank into a gutter section, an additional forming element in the form of an angle member and means for forcing said 50 additional forming element toward said forming roll to bend the unbeaded edge of said blank thereover, and lugs secured to said additional forming element and extended within said trough in position to be engaged 55 by said blank when the forming roll approaches its lowermost position, so as to move the operating means for said additional forming element in a position for convenient manipulation.
- 60 6. A mechanism of the character described including in combination, a channel base member, a plurality of supports therefor, a trough supported on said channel member, a beading rod mounted on one edge 65 of said trough and adapted to form a bead

on one edge of a sheet metal blank, a forming roll pivotally mounted, means for forcing said forming roll into said trough to form the blank into a gutter section, an additional forming element in the form of an 70 angle member and means for forcing said additional forming element toward said forming roll to bend the unbeaded edge of said blank thereover, lugs secured to said additional forming element and extended 75 within said trough in position to be engaged by said blank when the forming roll approaches its lowermost position, so as to move the operating means for said additional forming element in a position for convenient manipulation, said trough being formed of two sections, one of said sections being adjustably mounted on said channel iron, whereby the size of the trough may be varied, said forming roll being removably 80 mounted so that different sized rolls may be used.

7. A mechanism of the character described, including in combination, a support, a trough mounted on said support, said 85 trough being adjustable so that the size thereof, may be varied, a beading rod rotatably mounted on one side of said trough, a forming roll pivotally mounted on one side of said trough and means for moving said 90 forming roll into and out of said trough, a plurality of guiding members for one edge of the blank, said guiding members being adjustably and resiliently held toward said trough.

8. A mechanism of the character described, including in combination, a support, a trough mounted on said support, said trough being adjustable so as to vary the size thereof, a beading rod mounted on one 100 side of said trough adapted to form a bead in one edge of a sheet metal blank, a forming roll pivoted to one side of the trough, means for forcing said forming roll into said trough to form the blank in a gutter 105 section, a plurality of brackets extending upwardly from said support having slots provided therein, a guiding member for each bracket having means passing into said slot, resilient means for holding said guiding 110 members toward said trough, and an adjustable stop for limiting the inward movement of said guiding members, said guiding members being adapted to engage the unbeaded 115 edge of the blank.

9. A mechanism of the character described, including in combination, a support, a trough mounted on said support, said trough being adjustable so as to vary the size thereof, a beading rod mounted on one 120 side of said trough adapted to form a bead in one edge of a sheet metal blank, a forming roll pivoted to one side of the trough, means for forcing said forming roll into said trough to form the blank into a gutter 125

section, a plurality of brackets extending upwardly from said support having slots provided therein, a guiding member for each bracket having means passing into said slot, 5 resilient means for holding said guiding members toward said trough, and an adjustable stop for limiting the inward movement of said guiding members, said guiding members being adapted to engage the un- 10 beaded edge of the blank, and an additional forming element on the other side of said trough adapted to engage the unbeaded edge portion of the blank and means for moving said additional forming element to force said 15 unbeaded edge portion over said forming roll.

10. A mechanism of the character described including in combination, a trough into which a sheet metal blank is adapted to 20 be forced, a forming roll pivotally mounted on said trough and having means for forcing it into said trough for forming said blank into a gutter section, a beading rod mounted on the same side of said trough 25 and adapted to form a bead in one edge of said blank, and guiding means on the other side of said trough adapted to engage the unbeaded edge of said blank.

11. A mechanism of the character described including in combination, a trough into which a sheet metal blank is adapted to 30 be forced, a forming roll pivotally mounted on said trough and having means for forcing it into said trough for forming said blank into a gutter section, a beading rod mounted on the same side of said trough 35

and adapted to form a bead in one edge of said blank, bracket members extending from the other side of said trough and a resiliently held guiding member mounted on each 40 bracket member adapted to engage the unbeaded edge of said blank.

12. A mechanism of the character described including in combination, a support, a two-part channel-shaped trough mounted 45 on said support, means for adjusting said trough so as to vary the size thereof, a beading rod mounted on one edge of said trough adapted to form a bead in one edge of a sheet metal blank, a forming roll mounted 50 on one side of said trough and having means for moving said forming roll into and out of said trough, and means on the other side of said trough for bending the free edge of said blank over the forming 55 roll.

13. A mechanism of the character described, including in combination, a trough, a pivotally mounted forming roll, means for forcing said forming roll into said trough, 60 an additional forming element, an operating lever for said additional forming element, and means connected to said additional forming element and extended into said trough and adapted to be engaged by the 65 blank when the forming roller approaches its lowermost position so as to move said operating levers to a convenient position for operation.
